(57) **CLAIM**

The ornamental design for a display screen or portion thereof with graphical user interface, as shown and described.

DESCRIPTION

FIG. 1 is a front view of a first embodiment of a display screen or portion thereof with graphical user interface, showing our new design; and, FIG. 2 is a front view of a second embodiment of a display screen or portion thereof with graphical user interface, showing our new design.

The outermost broken lines in FIGS. 1-2 illustrating the display screen or portion thereof form no part of the claimed design. The remaining broken lines in FIGS. 1-2 illustrate portions of the graphical user interface that form no part of the claimed design.

1 Claim, 2 Drawing Sheets
